UNITED STATES PATENT OFFICE.

FREDERICK M. WHYTE, OF TARRYTOWN, NEW YORK, ASSIGNOR TO HUTCHINS CAR ROOFING COMPANY, OF DETROIT, MICHIGAN, A CORPORATION OF MICHIGAN.

CAR-ROOF.

1,354,637.

Specification of Letters Patent.

Patented Oct. 5, 1920.

Application filed November 1, 1917. Serial No. 199,736.

To all whom it may concern:

Be it known that I, FREDERICK M. WHYTE, a citizen of the United States of America, residing at Tarrytown, in the county of 5 Westchester and State of New York, have invented certain new and useful Improvements in Car-Roofs, of which the following is a specification, reference being had therein to the accompanying drawings.

10 The invention relates to car roofs, of that type in which the load-sustaining roofing sheets are relatively movable to permit adjustment to distortions in the car frame. It is the object of the invention to provide a 15 more thorough weather-proof joint between adjacent members without in any way interfering with their freedom of relative movement. To this end the invention comprises the construction as hereinafter set forth.

In the drawings:

Figure 1 is a sectional perspective view of a portion of the car roof, showing my improved construction;

25 Fig. 2 is a similar view, showing a slight modification;

Fig. 3 is a diagrammatic view showing a portion of the car roof of Fig. 1.

A and B are portions of two adjacent roofing sheets, which may be supported and secured down upon the roof frame (of which only a cross-section of a carline H is shown), in any suitable manner. The opposite side edges of these sheets are provided with up- 30 standing flanges, a single flange C being arranged at one side, and an open, returnbent flange D being arranged at the opposite side. Thus, when the two sheets are laid adjacent to each other, the returnbent flange D will 35 embrace the flange C, permitting freedom 40 for relative movement.

The construction as thus far described will not be thoroughly weather-proof, as the rain, cinders, etc., will find access to the interior of the car, passing under the returnbent flange D and blowing over the flange C. To render the structure completely weather-proof, I provide a cap member E, which is 45 of an inverted U or returnbent form, and is 50 preferably provided with foot flanges F and F'. One of these flanges is secured to one of the sheets A or B by riveting or otherwise, while the other flange bears upon the adjacent sheet. The U-shaped portion is of sufficient width to provide clearance on op-

posite sides of the returnbent flange D, so as not to interfere with freedom of movement. G is a securing device attached to the sheet, which is free from the member D and is adapted to hold the flange F' of said member down upon said sheet. As shown in Fig. 1, the member G comprises a flange extending parallel to the edge of the sheet and riveted or otherwise secured thereto, a portion of the flange being bent upward slightly 60 to form a groove for receiving the flange F'. In Fig. 2, a modified construction is shown, where a series of spaced clips G' are substituted for the continuous strip.

In use, the construction above described 70 will very thoroughly exclude the weather, while at the same time the sheets are freely movable. The weather-proofing is due to the fact that any water which may force its way beneath the flanges F and F' will only enter 75 the enlarged space between the U-shaped member E and the returnbent flange D. Even in case the inner pressure is sufficient to carry the water upward, it will still be excluded from entrance into the car by the 80 returnbent flange.

The construction described is applicable to various constructions of car roofs, but is particularly advantageous with that type in which the roofing sheets are rigidly attached 85 to supporting carlines but are permitted freedom of movement in relation to each other. Thus, as shown in Fig. 1, H are carlines, extending centrally of the sheets A and B and riveted or otherwise rigidly secured 90 thereto. The weather-proof joint is thus arranged midway between carlines and will permit of any relative movement occasioned by the weaving of the car frame.

What I claim as my invention is:

1. In a car roof, the combination with adjacent relatively-movable roofing sheets, of an upstanding flange on the edge of one of said sheets, an open returnbent flange on the opposite sheet embracing said upstanding flange and providing clearance for movement thereof, and a member of returnbent form embracing said first returnbent flange with clearance for relative movement, said second returnbent flange being secured to one of the 105 sheets.

2. In a car roof, the combination with relatively-movable roofing sheets, of an upstanding flange at the edge of one of said sheets, a returnbent flange at the edge of 110

- the adjacent sheet embracing said upstanding flange with clearance for relative movement, and a member of returnbent form embracing said first-mentioned returnbent flange, with freedom for relative movement, said second flange being secured to the sheet having the upstanding flange.
3. In a car roof, the combination with adjacent relatively-movable roofing sheets, of an upstanding flange along the edge of one of said sheets, a returnbent flange along the edge of the adjacent sheet embracing the upstanding flange with clearance for relative movement, a second returnbent or inverted U-shaped member embracing said first-mentioned returnbent flange with clearance for relative movement, said second member being provided with foot flanges resting upon the respective sheets, one of said foot flanges being rigidly attached to the sheet on which it rests, and means for holding down the opposite foot flange upon the sheet on which it rests.
4. In a car roof, the combination with relatively-movable adjacent roofing sheets, of an upstanding flange along the edge of one sheet, a returnbent flange along the edge of the adjacent sheet embracing the upstanding flange, with clearance for relative movement, an inverted U-shaped or returnbent member embracing said first-mentioned returnbent flange, with clearance for relative movement, said second member being provided with foot flanges resting upon the respective sheets, one of said foot flanges being rigidly attached to the sheet having said upstanding flange, and means for holding down the opposite foot flange upon the sheet having said returnbent flange.
5. In a car roof, the combination with relatively-movable adjacent roofing sheets, of an upstanding flange along the edge of one of said sheets, an open returnbent flange along the edge of the adjacent sheet embracing said upstanding flange, with clearance for relative movement, an inverted U-shaped or returnbent member embracing said first-mentioned returnbent flange, with clearance for relative movement and provided with foot flanges for resting upon the respective sheets, one of said foot flanges being rigidly secured to the sheet having said upstanding flange, and a strip secured to the opposite sheet, having a portion overlapping the other foot flange, for the purpose described.
6. In a car roof, the combination with carlines, of roofing sheets rigidly secured to the respective carlines and extending adjacent to each other, an upstanding flange on the edge of one of said sheets, an open returnbent flange upon the edge of the adjacent sheet, embracing said upstanding flange, with freedom for relative movement, a returnbent or inverted U-shaped member embracing said first-mentioned returnbent flange with clearance for relative movement and provided with foot flanges resting upon the respective sheets, one of said flanges being rigidly attached to the sheet on which it rests, and means for holding down the opposite flange upon the sheet on which it rests, permitting relative movement.
7. In a car roof, the combination with adjacent relatively-movable roofing sheets, having upstanding flanges on adjacent edges, of a cap embracing said flanges and secured directly to one of said sheets.
8. In a car roof, the combination with adjacent relatively-movable roofing sheets having upstanding flanges on adjacent edges, of an inverted U-shaped cap embracing said flanges and provided with foot-flanges, one of said foot-flanges being rigidly attached to one of said roofing sheets, and means upon the other sheet for holding down the other foot-flange adjacent to the other sheet.
9. In a car roof, the combination with carlines, of roofing sheets secured to the respective carlines and having unsupported upstanding flanges on their edges adjacent to each other, one of said upstanding flanges being return bent to embrace the other with freedom for relative movement, and a cap member embracing said flanges and secured to said roofing sheets.
10. In a car roof, the combination with carlines, of relatively movable roofing sheets rigidly secured to the respective carlines and having unsupported upstanding flanges on their edges extending adjacent to each other, one of said flanges being return bent and embracing the other of said flanges with freedom for relative movement, an inverted U-shaped member embracing said return bent flange with clearance for relative movement, said member being rigidly attached to one of said roofing sheets and movably attached to the other of said roofing sheets.
11. In a car roof, the combination with carlines, of relatively movable roofing sheets centrally secured to said carlines, an upstanding flange on the edge of one of said sheets, an open return bent flange on the opposite sheet embracing said upstanding flange and providing clearance for movement thereof, and an inverted U-shaped cap embracing said return bent flange with clearance for relative movement, said cap being rigidly secured to one of said roofing sheets and movably secured to the other.

In testimony whereof I affix my signature in presence of two witnesses.

FREDERICK M. WHYTE.
